HEAT EXCHANGER

Samuel Cornette Collins, Watertown, Mass., assignor to Joy Manufacturing Company, Pittsburgh, Pa., a corporation of Pennsylvania

Application January 20, 1948, Serial No. 3,217

2 Claims. (Cl. 257—245)

1

My invention relates to heat exchangers and particularly to heat exchangers which are well adapted, though by no means confined, to use in plants for the separation of gases.

The chief criterion of a superior heat exchanger is its efficiency, which is based upon the quantity of heat transferred per degree in difference of temperature between the counter-streams. Such efficiency can be promoted, I have found, by providing constructions in which the material streams separated by and caused to flow at opposite sides of relatively thin walls through which heat transfer is to be effected are made laterally of relatively great dimension compared with what might be called their depth, and by placing in the streams of materials many turbulence creating obstructions—obstructions which do not unduly interfere with the movements of the desired quantities of fluid but which nonetheless result in a continuous internal remixing of the masses of flowing fluids, so that stratified temperature changes are avoided, and so that layers which have been warmed (or cooled) in such a manner as substantially to reduce the temperature differential between them and the walls which they contact are mixed with the portions of the fluids which differ more substantially in temperature from such walls. Moreover, I have found that by utilizing plates having projections or protuberances extending in opposite directions from their principal planes, and placing plane plates in alternation with the plates having the projections or protuberances formed thereon, it is possible to produce a construction which accomplishes the advantages mentioned above and which also possesses sufficient strength to permit substantial pressure differentials at the opposite sides of any of the walls thereof. For convenience in reference to them, but not by way of limitation, I will refer to the plates having projections from them as being dimpled or beaded plates, meaning thereby that the metal is deformed so as to provide hollow domed or concavo-convex projections therefrom. Except as may be necessitated by the prior art or indicated in the appended claims, however, the feature of the hollowness of the projections is not to be considered an essential characteristic of the beaded plates. However, when I use the term "dimpled," it is to be understood as denoting the use of recessed projections. I have further found that by utilizing plates as set forth, with partition elements as in the form of bent wires arranged between adjacent plates, and by the use of appropriate headers with, in some cases, separator rings as well as other separator

2

elements, a very readily constructed as well as efficient heat exchanger can be provided. I have further found that the employment of telescoping or nesting pan sections with protuberances projecting outwardly from the pan sections a distance sufficient to engage other pan sections provides a very simple and strong heat exchanger, and that instead of protuberances formed from the metal of and projecting from the pan sections or plate sections other turbulence and stiffness providing structures may be employed as hereinafter set forth.

It is an object of my invention to provide an improved heat exchanger, meeting the standards of efficiency above set forth and readily constructed. It is another object of my invention to provide an improved heat exchanger. It is a further object of my invention to provide an improved heat exchanger employing improved passage forming means for the confining and guiding of the fluid treated therein. It is a further object of my invention to provide an improved heat exchanger having improved means operative both to improve its efficiency of performance and to adapt it for use with fluids which may be at opposite sides, under substantially different pressures, of separating heat transfer walls. It is another object of my invention to provide an improved heat exchanger having improved header elements and header arrangements. It is still another object of my invention to provide an improved heat exchanger having improved passage forming elements. It is yet a further object of my invention to provide an improved heat exchanger having improved turbulence creating elements arranged in the flow passages thereof. It is still another object of my invention to provide an improved heat exchanger having improved heat transfer effecting arrangements. It is another object to provide an improved heat exchanger element. Other objects and advantages of my invention will hereinafter appear.

In the accompanying drawings, in which a number of illustrative embodiments and several modifications which my invention may assume in practice are shown,

Fig. 1 is an elevational view of a vertically disposed heat exchanger, parts being broken away to show interior construction, and a substantial section between the ends of the device also being broken out to reduce the space required by the view.

Fig. 2 is another elevational view of the structure which is shown in Fig. 1, turned through

90° and partially broken away to show details of construction.

Fig. 3 is a vertical section on the plane of the line 3—3 of Fig. 2.

Fig. 4 is a fragmentary horizontal sectional view on the plane of the section line 4—4 of Fig. 3.

Fig. 4A is an enlarged, fragmentary horizontal section, on a plane corresponding to the line 4—4 of Fig. 3, showing a modified arrangement for maintaining the elements of a heat exchanger held together.

Fig. 5 is a fragmentary horizontal sectional view on the plane of the line 5—5 of Fig. 3.

Fig. 6 is a face view of a gasket used between a header and the main bank or package of heat exchange elements.

Fig. 7 is a view generally similar to Fig. 1, but without parts broken away, the arrangement being one for the effecting of heat interchange between three, rather than two, fluids.

Fig. 8 is a fragmentary view of a portion of the structure shown in Fig. 7, turned through 90°, partially in elevation and partially broken away, to show details of construction.

Fig. 9 is a fragmentary sectional view on the vertical plane of the section line 9—9 of Fig. 7.

Fig. 10 is a similar view on the plane of the section line 10—10 of Fig. 7.

Fig. 11 is a vertical sectional view on the plane of the section line 11—11 of Fig. 8.

Fig. 12 is a corresponding vertical section on the plane of the line 12—12 of Fig. 8.

Fig. 13 is a vertical section on the plane of the line 13—13 of Fig. 8.

Fig. 14 is a horizontal transverse section on the plane of the line 14—14 of Fig. 7.

Fig. 15 is a horizontal transverse section on the plane of the line 15—15 of Fig. 7.

Fig. 16 is a face view of a gasket.

Fig. 17 is an elevational view with parts broken away showing a modified form of two pass or two course heat exchanger.

Fig. 18 is another elevational view of the structure shown in Fig. 17, turned through 90° and with parts broken away to show internal construction.

Fig. 19 is a vertical longitudinal sectional view taken on the plane of the line 19—19 of Fig. 17, central portions of the view being omitted to reduce the size requirements of the drawing, the view being on an enlarged scale.

Fig. 20 is a view similar to Fig. 19, taken on the plane of the section line 20—20 of Fig. 17.

Fig. 21 is a vertical sectional view on the plane of the line 21—21 of Fig. 19.

Fig. 22 is a fragmentary horizontal transverse sectional view on the plane of the line 22—22 of Fig. 21.

Fig. 23 is a view on a somewhat larger scale showing a pan form plate section adapted for use in an exchanger of the type shown in Figs. 17 and 18.

Fig. 24 is another view of the pan or plate section of Fig. 23, turned through 90°, with parts broken away to show details of construction.

Fig. 25 is an enlarged fragmentary vertical sectional view on the plane of the section line 25—25 of Fig. 23.

Fig. 26 is an enlarged fragmentary vertical sectional view on the plane of the line 26—26 of Fig. 23.

Fig. 27 is an elevational view, shortened in

length, of a plane sided pan section utilizable with the pan section of Fig. 23.

Fig. 28 is a view similar to Fig. 24, but showing the plane sided pan section.

Fig. 29 is a vertical sectional view approximately on the plane of the line 29—29 of Fig. 23.

Fig. 30 is a considerably enlarged fragmentary sectional view showing details of construction of the nested pans of Fig. 29.

Fig. 31 is a view similar to Fig. 23 showing another arrangement of means for effecting turbulence and preventing collapse of the heat exchanger structure.

Fig. 32 is an enlarged fragmentary vertical sectional view on the plane of the line 32—32 of Fig. 31.

Fig. 33 is a fragmentary view, with parts partially shown in full, on the plane of the section line 33—33 of Fig. 32.

Fig. 34 is an enlarged fragmentary view showing a detail of construction on a larger scale than Fig. 32 shows this structural arrangement.

Fig. 35 is a view similar to Fig. 34, showing a further modification.

Referring to the drawings, and first to sheet #1 thereof, it will be noted that on this sheet I have illustrated an improved heat exchanger construction adapted for the effecting of heat transfer between two oppositely moving relatively wide and relatively shallow streams of fluid, and having improved means for effecting a substantially continuous remixing of the fluids of the individual streams as they pass through the heat exchanger. This heat exchanger, generally designated 1, includes a pair of headers 2 and 3, and a bundle or package 4 of plate elements 5 and 6, and outside plates 7 and 8. There are also provided partition elements 9, gaskets 10, and holding means 11 and 12, the former holding the bundle of plates tightly together, and the latter holding the headers to the bundle of plates.

The plates 5 are plane and quite thin and are made of metal such as aluminum or stainless steel, and desirably are many times as long as they are wide. Such metals are chosen to reduce heat loss by conduction within the metal of the plates between the hot and cold ends of the exchangers. The plates 6, which alternate with the plates 5, are of similar material and are plane except that they have pressed from their opposite surfaces protuberances 15, these protuberances in the construction shown each being in the form of a concavo-convex or hollow rounded projection; and, by reason of the hollow nature of these projections, the plates may from one aspect be regarded as "dimpled," each dimple being the recess within a hollow projection. For some purposes, beads might simply be formed on the plates without hollow recesses, but this would be somewhat less advantageous from the angle of simplicity of manufacture, for the plates 6 can now simply be rolled between suitably constructed rollers and have the oppositely extending protuberances 15 formed on the same pass between the rolls. However, as above noted, my invention, except as expressly limited thereto, is not confined to hollowed out protuberances.

The plate package 4 consists of a considerable number of plates 5 alternating with plates 6, and this bundle of plates has at the sides thereof, the thicker, relatively rigid, outside plates 7 and 8. The protuberances 15 provide for relatively uniform spacing between the plates 5 and 6 and between the outermost plates 6 and the outside plates 7 and 8. The edges of the channels formed

between the plates 5 and 6 and between the plates 6 and the outside plates 7 and 8 require sealing, and it is also desirable to seal, in the construction now being described, something more than one-half of each end of these passages, but to leave openings 16 and 17 diagonally opposite each other at the ends of the passages. For the purpose of providing the seals, the sealing elements or wires 9 are employed, and it will be noted, referring to Fig. 3, that these are in this case approximately L-shaped, and include longitudinally extending portions 9L and transversely extending portions 9E, the latter extending from one edge of the plates between which they are disposed to a point beyond the middle of the ends of the plates, so that they may prevent the communication of certain header passages with certain of the flow passages between the plates. These flow passages may be herein-after referred to as F¹ and F², F¹ being the passage through which one of the fluids is to flow from one end of the exchanger to the other and F² being used to designate the alternate flow passages employed for the conducting of the other of the two fluids in an opposite direction from the second end to the first. The headers 2 and 3 each contain two chambers extending for substantially their full depths. The chambers in the header 2 are numbered 21 and 22, while the chambers in the header 3 are numbered 23 and 24. Between each header and the bundle 4 there are gaskets 10, and each gasket has two openings in it, O₁ and O₂. The gaskets are applied to the ends of the plate bundle 4 and the headers are secured against the gaskets by means of the holding means 12, shown as consisting of vertically extending bolts 26 having nuts 27 engageable directly or through suitable lock washers with flanges 28 on the headers, the bolts extending through the gaskets and also through flanges 29 formed on the outside plates 7 and 8. The chambers 21, 22, 23 and 24 each have conduits connected to them, these being numbered respectively C₂₁, C₂₂, C₂₃, and C₂₄, the conduits being secured in place as by studs 30 and nuts 31 with the studs passing through flanges 32 secured to the conduits. Flanges 33 may be fixed to the ends of the plate elements 5, 6, 7 and 8 and separators 9 to strengthen the construction. The separators are soldered or brazed in position, and may be individually brazed or soldered, or may be held in position by dipping the bundle in a suitable container containing molten solder or brazing material.

The soldering or brazing of the various plate elements and separators together will provide a relatively strong fluid-tight construction, but additional means for increasing the ability of the heat exchanger to resist pressures in directions at right angles to the planes of the flow passages may be provided, as at 11 above mentioned. For example, in Figs. 1 to 6 (excluding Fig. 4A) threaded tie rods 34 equipped with suitable nuts 35 at their opposite ends are shown extended through the edges 36 of the outside plates 7 and 8, further securely to hold the exchanger components together. Another arrangement for providing for a very secure and strong holding of the parts together consists in the tipping of each of the protuberances 15 with silver solder or the like before the plates are brought together in a completed stack, and then, by appropriately heating up the entire bundle of plates sufficiently to cause the silver solder to effect connections as at 38 of the various protuberances to the plane plate surfaces which

they contact, an exceedingly strong structure will be produced, for the number of ties in tension between the plates will be very large. Such an arrangement is illustrated in Fig. 4A, and with this form of arrangement it is unnecessary to use the tie rods 34 and nuts 35, though there is no objection to doing this, if it be desired.

The presentation of more extended description of this embodiment of the invention is scarcely necessary, but it may be pointed out that one fluid may enter through the conduit C₂₂ into the chamber 22 and flow through all of the passages F¹ to discharge at the opposite end of the heat exchanger into the chamber 23 of the header 3 and be delivered through the conduit C₂₃, while simultaneously fluid delivered to the heat exchanger through the conduit C₂₄ may flow from the chamber 24 into the passages F² and out into the chamber 21 in the other header 2 and be led away by the conduit C₂₁. Because of the diagonal flow of the fluids, there will be a practically complete elimination of dead spots in the passages, and maximum efficiency of heat exchange will be secured. Because of the protuberances 15, even if there is a substantial difference in pressure in the different passages, there will be no serious tendency of the exchanger structure to collapse. Because also of the presence of these many protuberances arranged desirably for convenience in manufacture in longitudinal and transverse rows, the flowing streams of material will be subjected to recurrent turbulences which will effect reminglings of the warmer portions of the streams with the cooler portions thereof, and thus the maintenance of best conditions, i. e. maximum temperature differential, between the fluids at opposite sides of the plate elements, will be accomplished.

The three pass or course heat exchanger shown on sheet #2 of the drawings (in Figs. 7 to 16) does not require such extended description of its structure, because its essential differences from the first form of the invention described inhere only in the modifications necessary to adapt the structure to the effecting of heat exchange among three streams of fluid. The following may be noted by way of preliminary. Since the invention is being illustrated in forms of construction particularly adapted for use in apparatus for the separation of air into its constituents, and since, in a preferred form of this type of apparatus where the fluids, when but two are involved, are air and the nitrogen constituent of the air, these fluids are desirably caused to flow alternately now in one and now in the other course of the heat exchanger intended for their confinement and guidance, the two passages, where but two are used, and the two principle passages, where there are more than two passages present, will be made of equal flow capacity. Where the oxygen, however, is also to be passed through the heat exchanger, it will require no such flow area as the nitrogen and the entering air require, as the oxygen is only about one-fifth, by volume, of the air. Accordingly, while the air and nitrogen conducting passages will be maintained substantially the same in number and in construction as in the first described embodiment of the invention, there will be interspersed among the air and nitrogen carrying passages a distinctly smaller number of oxygen conducting passages. And the headers will be modified to provide three sets of chambers, an

intermediate set of chambers 41 and 42 in addition to the chambers 21', 22', 23' and 24'. Similarly, there will be an intermediate opening O3 in each of the gaskets 10'. The partition elements must assume three forms in this embodiment of the invention, and while the partition elements 9' will have their portions 9L' constructed similar to the portions 9L of the partition elements 9, the portions 9E' will have to be lengthened so as to overlie the mouths of the central passages 41 or 42—and of the openings O3—as well as one of the larger chamber mouths. There must, however, also be, further, new type partition members 49, each of which will have a portion 49E at both ends thereof. In other words, the members 49 are in the form of shallow U's with the open ends of pairs of these elements extending towards each other and spaced apart as at 50 so as to permit the chambers 41 and 42 and the openings O3 to communicate with the passages between plates which are separated from one another by the new forms of elements 49.

Referring to Fig. 15, it will be observed, starting at the top of the figure as viewed in the drawings, that there is a passage F1, then a passage F2, then, if oxygen be the other fluid to be passed through the heat exchanger, an oxygen conducting passage F3, and then, before the next recurrence of an oxygen conducting passage F3 there will be found another passage F1, another passage F2, a further passage F1, and a further passage F2. Thereafter, following the next passage F3 there will be two other pairs of passages F1 and F2 before the next passage F3. The particular number of passages F1 and F2 for each passage F3 is not to be regarded as critical, as there might be even more passages F1 and F2—even as many as four or five of each, for each passage F3.

This modification does not need further detailed description. Conduits 51 and 52 held by studs and nuts 53 and 54 to the headers 2' and 3' serve for the conducting of oxygen relative to the chambers 41 and 42. The headers are held in position relative to the other structure, and the outside plates and the individual plates are secured together and sealed, in a manner or manners similar to those described with respect to the first embodiment of the invention. It will be evident that through certain passages, air and nitrogen flow in alternation in heat exchange relation to each other; that through certain other passages air and nitrogen flow in heat exchange relation to the oxygen. The precise arrangement, however, of the passages need not be as illustrated and, for example, there might be an air conducting passage at each side of each oxygen conducting passage. The turbulence effected, the remixing of the fluids in the individual streams, the additional heat transfer area provided by the protuberances, the very efficient heat exchange accomplished by the thin streams and thin wall members, and the reinforcement against fracture of the plates or collapse of the passage forming walls are all present with this construction also.

Desirably, valve means will be provided and arranged in association with the heat exchangers so far described, so as to cause the nitrogen always to flow in one direction and the air to always flow in the other direction regardless of which passage series may be conducting nitrogen and air, and desirably the oxygen will always flow in one direction—counterflow to the air when the construction of sheet #2 is employed.

While references have been made to nitrogen, air and oxygen, it will be understood that these have been referred to because of the reference to the special suitability of the heat exchangers illustrated and described to air separation adjuncts, but my invention is in no sense limited to these elements or even to gases and/or vapors.

The structure of sheet #3, namely that shown in Figs. 17 to 22, may next be considered. The principal difference of this two-pass heat exchanger from the construction first described resides in the manner of and the structure for effecting distribution of the fluids to be treated in the heat exchanger through the passages provided between the plates. It will be observed, referring particularly to Figs. 19 and 20, that the plates 6'', which are provided with the protuberances 15, and the plane plates 5'' are each provided adjacent its opposite ends with pairs of circular openings 60 and 61, it being noted that the openings 60 are formed in the plates 6'' and the openings 61 in the plates 5''. These openings are in line with each other, and, accordingly, without additional structure all of the passages between the plates would be in communication with each other. Accordingly, I provide rings 63 associated with certain of the plates as herein-after described, these rings being of the same internal diameter as the openings 60 and 61 and the same thickness axially as the projection of the protuberances 15 from the plates 6''. Outside plates 7'' and 8'' are provided, the outside plates 8'', except for dimension, being not different in any substantial way from the outside plates 3. The outside plates 7'', however, are provided with thickened annular portions 64 providing seats 65 to which conduits 66 may be held by suitably threaded means 67, the seats being traversed by openings 68 which line up with the openings 60 and 61.

In order to distinguish the parts more readily during further explanation, the four conduits 66 may be identified individually as 66', 66'', 66''', and 66'''', and the openings 68 may correspondingly be individually identified as 68', 68'', 68''', and 68''''.

Now it may be desired to cause fluid to enter through the opening 68' and to pass through one-half of the passages between the plates and to leave the heat exchanger through the diagonally opposite opening 68''''. It will then be desirable to have the other fluid to be treated in the exchanger enter through the opening 68''' and leave through the opening 68''. It is, therefore, necessary to seal off certain passages between the plates from communication with the openings 68' and 68'''' and to seal off certain other passages from the openings 68''' and 68''. This sealing off is effected by the rings 63. Accordingly, referring now to Fig. 20, it will be observed that there is no ring 63 between the outside plate 7'' and the adjacent plate 6'', in coaxial relation with the opening 68', while there is a ring coaxial with the opening 68' between the above mentioned plate 6'' and the adjacent plane plate 5'', and this arrangement of rings and plates continues to the outside plate 8'' of the heat exchanger with respect to the openings through the plates which are coaxial with the opening 68'. Referring next to Fig. 19, it will be observed that with respect to the openings coaxial with the opening 68''', the rings 63 are arranged just the same as they are with respect to the opening 68', and, accordingly, assuming the direction of flow inward at 68' and out at 68''''.

it will be observed that flow takes place through the first, third, fifth, etc. passages between the plates from 68' to 68'''. With respect to the flow in the other series of passages between the plates, it may be observed that with respect to the openings coaxial with the opening 68''', there is a ring between the outside plate 7" and the adjacent plate 6", while there is no ring between this plate 6" and the plane plate 5" immediately next to the aforesaid dimpled plate 6". This arrangement of rings 63 continues to the outside plate 8" of the stack. With respect to the opening 68'' at the opposite end of the exchanger, it will again be noted that there is a ring between the outside plate 7" and the adjacent one of the dimpled plates 6" and no ring between this plate 6" and the adjacent plane plate 5". This type of ring arrangement continues also to the outside plate 8". Accordingly, fluid entering through the opening 68''' may leave after moving through the full length of the passages which communicate with the opening 68''' out through the opening 68'', flowing in counterflow relation to the fluid entering 68' and leaving at 68'''. The rings in this construction will be brazed or soldered to the plates at each side of them and because the headers are between the ends of the plates, the seals 70 may be caused to run all the way around the outside edges of the various plates, being brazed or soldered to the plates in any suitable manner as previously suggested. The wires or seals (or partition members) 70 may be round or square in cross section, or of any other desirable shape. Cross bars 71 and tie bolt devices 72 may be arranged to clamp the heat exchanger elements firmly together, these clamps being arranged adjacent the extreme end of the exchanger unit and also at various appropriate points along its length. They remove the necessity for reliance exclusively on brazing or soldering to hold the parts of the units together. This construction needs no general description, because it is obvious that one fluid entering at one corner will pass through one-half of the passages between plates and out at the diagonally opposite corner, while the other fluid will enter at the opposite side of the end of the heat exchanger at which the first fluid leaves and will itself emerge from the diagonally opposite corner of the exchanger. The turbulence, the internal reinforcing, the effective heat transfer through thin plates, the strong and rugged construction, and other features of the earlier illustrative embodiments are obviously present in this construction also. As with respect to the first construction described, there may be in this and also in the last preceding form brazing or soldering of protuberances to adjacent plates, for greater strength and increased heat transfer.

Turning now to the modifications disclosed on sheet #4 of the drawings, in Figs. 23 to 35, the specific modification shown in Figs. 23, 24, 25, 26, 27, 28, 29 and 30 may be first noted. There is, practically speaking, but one difference between this modification and the modification shown in Figs. 17 to 22 inclusive. This difference resides in the making of the plates and the partition elements in the form of nesting pans. In other words, each of the dimpled plates 6''' is provided with a dimpled upright section 75 and a peripheral flange portion 76, the flange portions sloping outwardly in each case with respect to the upright section 75, and projecting laterally from the upright section 75 a greater distance than do the protuberances 15. The plate sections

5''' are also formed with plane upright sections 77 and outwardly flaring flange portions 78, so that they are in the form of shallow pans, and the flare of the flange portions 76 and 78 is such that when a pan section 5''' is slipped into and placed with its plane portion in contact with the protuberances 15 on a section 6''', there will be substantial contact between the flanges on the two sections as well as substantial contact between the protuberances and the upright section of the overlying pan section. In like manner, the opposite lateral projection of the protuberances 15 from the upright section of a pan or plate section 6''' is such that when these contact the plane surface of an upright section of a pan or plate section 5''' into which the section 6''' is fitted, the outer walls of the rim or flange 76 will contact the inner wall of the rim or flange 78. Thus, simply by flowing solder into the joints between the rims or flanges of the various plate or pan sections, or by brazing these rims or flanges together, a very effective heat exchanger can be secured, it being necessary, however, still to use rings 63 in connection with the openings which are provided to establish communication between the supply and discharge connections and the passages between the plates. All of the advantages of the modification of the invention last described, plus the further advantage of a simple and very rugged and very easily and effectively sealed heat transfer unit, are present in this modification of Figs. 23 to 30.

It will be understood that by appropriately cutting away the end flanges on the plates—as by cutting completely away perhaps two-fifths at diagonally opposite corners on one series of pans and perhaps two-fifths at the other diagonally opposite corners on the other series of pans and using end headers as in the first embodiment described, the large openings 60, 61 and the rings 63 can be omitted, and it will further be understood that additional strength can be attained by soldering the tips of the protuberances to adjacent plates as in Fig. 4A.

Many of the advantages of the invention can be obtained without employment of the dimpled plates, and it is possible, for example, to use entirely plain plates having plane upright sections and peripheral flanges as in the modification last described, and to provide, instead of the dimpling, rows of helically wound metal ribbon arranged transverse to the direction of longitudinal flow of the fluids through the heat exchanger. These helically wound ribbons will extend, except where interruptions may be necessary because of the openings through the upright sections of the pan, tray, or plate sections, completely from side to side of these sections. If it be desired, in the interest of ease of winding the ribbons in helices, to increase the distance between the adjacent parallel surfaces of the adjacent plates, the angle of the pan rims may be changed in such manner as to cause contacts with the helices and between the rims to occur substantially simultaneously. The helices may be initially bonded, as by brazing or soldering, to the opposite sides of a single plate, and if desired upon the assembly of the unit, brazing or soldering of the opposite sides of the helices to the plates which are brought into contact with them may be effected.

Referring briefly first to Fig. 31, it will be noted that there are a plurality of helices, as of aluminum or stainless steel, or other suitable wire, shown at 80, extending transversely to the

length of the plates 81. The plates 81 have the laterally extending flanges 82 which are adapted to contact with each other, as at 83, and to be brazed or soldered together when the units are assembled. Some of the units have plain upright sections designated as 81P, and others have secured—brazed or soldered—to their upright sections 81H the helically wound metallic ribbons 80, these being bonded to the upright sections 81H as indicated at 85. If desired, by dipping the unit or in any other appropriate manner, there may be an effective bonding of the helices at their sides contacted by the plain upright sections 81P, as shown at 86 in Fig. 35. With this construction, the flow through the passages formed between the partition forming portions 81P and 81H of the pan sections will be accompanied by very effective turbulence with the result that there will be a continuous remixing of each flowing fluid. There will also be a highly efficient heat exchange, because the helically wound wires provide a very large area for the effecting of heat transmission, and by their bonding to the plates, insure the rapid transfer of the heat which they may absorb to the adjacent plates.

Since the fluid distribution through this particular illustrative embodiment of the invention will be the same as in the last two described, it needs no detailed noting at this point. It will be observed, however, that a very rugged structure is produced because the convolutions of the helices being much closer together than the dimples, will provide the equivalents of struts between the plates at closer intervals.

It will be observed that the remixing of the portions of each fluid as it flows through this heat exchanger will be virtually continuous, and that the heat transfer effecting areas will be much increased.

It will be understood that the end type of manifolding illustrated with respect to the first species of the invention may be applied equally well to all other species shown as having a different form of manifolding, it being necessary only to remove at appropriate points portions of the separators, rims or flanges and to provide and secure in position the end type headers and gaskets.

In all the forms of the invention disclosed, 50 exceedingly effective heat exchange will be accomplished. In all the forms a rugged structure is secured and despite the minimization of wall thickness these heat exchangers can be used with fluids under quite different degrees of pressure. In all forms, though more so in some than in others, a readily assemblable and effectively sealable construction is provided. In all forms, the feature of turbulence within the flowing fluids is present. Turbulence due to changes in velocity as well as turbulence by the creation of eddies and impingements on transverse surfaces will be observed to be present in various embodiments disclosed. On the

whole, it will be observed that each embodiment of the invention well meets the criterion of efficiency set forth earlier in this specification.

While there are in this application specifically described five forms and certain modifications which the invention may assume in practice, it will be understood that these forms and modifications of the same are shown for purposes of illustration and that the invention may be further modified and embodied in various other forms without departing from its spirit or the scope of the appended claims.

What I claim as new and desire to secure by Letters Patent is:

1. A heat exchanger comprising a series of nested shallow pans defining narrow flow passages, and turbulence creating means cooperatively associated with said pans in said flow passages for repeatedly remixing the portions of the fluid flowing through said passages, said turbulence creating means being in the form of helical coils arranged cross-wise in said flow passages and secured to both sides of the bottoms of alternate pans only, the pans between 25 said alternate pans being in contact with but not secured to the coils.

2. In combination, in a plate type heat exchanger, a plurality of heat conducting plates each having a multiplicity of closely packed helical coils secured to both sides of the plate and a rim flaring outward from said plate and extending above the tops of said coils, a plurality of other plates each having a rim or side wall flaring outward therefrom, said last-mentioned 35 plates being plane and said plates of said first type and of said second type being arranged in alternation with said rims or side walls nested in each other, said plane plates contacting said coils on said other plates and concurrently engaging with their rims or side walls the rims or side walls of said other plates and said plates being bonded together at the contacting portions of said rims or side walls.

SAMUEL CORNETTE COLLINS.
